UNITED STATES PATENT OFFICE.

ANDREW R. KOEHLER, OF BUFFALO, NEW YORK.

MACHINE FOR REMOVING WAX FROM PLATES.

Application filed January 20, 1926. Serial No. 82,526.

This invention relates to a machine designed for removing wax from plates or cases which have been previously used for the production of wax impressions in the manufacture of the electrotypes.

Heretofore, the wax has been removed from such plates by laying such plates or cases on a heated surface so as to soften the wax and then scraping the wax from the plates or cases after which these plates and the wax may be used over again for making further electrotype matrices therefrom.

This method is not only slow and laborious but it also is difficult to thoroughly clean the plates or cases thereby rendering it possible to produce imperfect electrotypes on such plates.

It is the object of this invention to provide a machine whereby the wax may be removed from such plates efficiently and expeditiously and at a minimum cost and not only leave the plates in a perfectly clean condition so that they are ready for immediate use but also enable an electro-plating plant to operate without necessitating the employment of an undue number of plates or cases as has heretofore been necessary by reason of the delay in removing the wax from the plates or cases and getting them ready for new impressions.

With this object in view this invention consists generally of the instrumentalities which are shown in the accompanying drawings and which are constructed and operated in the manner as will presently appear.

In the accompanying drawings:—

Figure 1, is a side elevation of the machine for removing wax from plates or cases in accordance with my invention.

Figure 2, is a vertical longitudinal section of the same taken on line 2—2, Fig. 1.

Figure 3, is a top plan view of the machine.

Figure 4, is a front elevation of the same.

Figure 5, is a vertical cross section taken on the correspondingly numbered line in Fig. 1.

Figure 6, is a fragmentary, horizontal section on an enlarged scale taken on line 6—6, Fig. 1.

Figures 7 and 8 are fragmentary, longitudinal sections on an enlarged scale taken on the correspondingly numbered lines in Fig. 3.

Figure 9, is a fragmentary top plan view of a portion of the feed table over which the

wax-coated plates are adapted to be moved during the operation of removing the wax therefrom.

Figure 10, is a vertical section taken on line 10—10 Figure 9.

Figure 11, is a perspective view of the links of a chain forming part of the carrier or conveyer whereby the wax-coated plates or cases are propelled through the machine.

Figure 12, is a fragmentary-side elevation of the rear part of the machine showing the mechanism for lowering the plate stacking or receiving table, and adjacent parts.

Figure 13, is a similar view showing more particularly part of the mechanism whereby each plate is shifted from the main conveyer to the stacking table.

Similar characters of reference indicate like parts throughout the several views.

In its general organization this machine comprises means for propelling the wax-coated plates or cases, means for heating the plates while passing through the machine and melting the wax which has been previously deposited thereon, means for scraping from the plates any remnants which may be left thereon after being subjected to the heating operation, means for pressing the plates so as to straighten them and leave them in condition ready to be used over again, means for discharging the plates successively from the wax removing mechanism, and means for stacking the clean plates in a pile ready for use.

The main frame which supports the various working parts of the machine may be of any suitable construction but as shown in the drawings the same consists essentially of a main bed 20 arranged horizontally and lengthwise of the machine and two standards 21, 22 which support the front and rear ends of the bed.

On the upper part of the bed is arranged a horizontal table 23 which extends nearly the full length of the machine and above this table is arranged a horizontal cover 24 which extends only over the central part of the table thereby forming between this table and the cover a horizontal longitudinal passage through which the wax-covered plates 25 are moved lengthwise of the machine. When starting the wax-covered plate through the machine the operator places the same with its

uncoated under side upon the rear part of the table 23 which extends rearwardly beyond the rear end of the cover 24 so that the wax coating 26 on the upper side of the plate is exposed. After the wax cutting plate is thus placed upon the rear or receiving end of the table the same is carried forwardly over the table and through the space between the same and the cover 24 and subjected to the devices which operate to remove the wax from the upper side of the plate and also operate to straighten the plate if the same should become warped or bent while manipulating the same. Various means may be provided for thus propelling or conveying the same over the table, the conveying means for this purpose shown in the drawings being preferably constructed as follows:

The numerals 27, 27 represent two conveyer belts arranged side by side and preferably constructed in the form of link chains each of which passes forwardly with its upper operative stretch through a longitudinal groove 28 in the top of the table while its lower operative stretch passes backwardly underneath the table and its rear or receiving turn passes around a sprocket wheel 29 at the rear end of the table and its front or delivery turn passes around a front sprocket wheel 30 adjacent to the front end of the table. The receiving sprocket wheels 29 of both conveyer chains are mounted on a transverse shaft 31 which is journaled in suitable bearings on the bed of the frame and the delivery sprocket wheels 30 of both of these chains are mounted on a delivery shaft 32 which is journaled horizontally and transversely in suitable bearings on the adjacent part of the bed. Power for driving this belt may be derived from any suitable source and transmitted to the conveyer chains or belts in various ways, those shown in the drawings being merely an example of one suitable for this purpose and as there shown this power source consists of an electric motor 33 mounted on the front standard 21, an intermediate shaft 34 journaled in a bearing 35 on the front standard 21, a lower chain belt 36 passing around a sprocket pinion 37 on the shaft of the motor and a sprocket wheel 38 on the intermediate shaft, and an upper chain belt 39 passing around a sprocket pinion 40 on the intermediate shaft 34 and a sprocket wheel 41 on the front shaft 32 which carries the front conveyer sprocket wheels, as shown in Figs. 1 and 3. At suitable intervals the two chains of the conveyer are connected by transverse carrying wings or flights 42 each of which upon reaching the rear part of the table and beginning its forward movement relatively thereto is adapted to engage with the rear edge of a wax-coated plate and move the same forwardly over the table and pass the devices which subsequently operate thereon for removing the wax and straightening the plate.

The movement of this carrier is comparatively slow so as to give the wax removing and plate straightening devices ample time to perform their operations effectively.

In order to permit the operator to manipulate the plates more easily while the same are resting on the rear part of the table and bring the same substantially into their proper position for engagement of the wax or carrying plates of the conveyer anti-friction means are provided on this part of the table which engage with the under side of the wax-coated plate. The preferred form of this anti-friction device consists of a plurality of bearing balls 43 each of which is seated with its lower part in a socket 44 in the upper rear part of the table and is retained loosely therein by means of a retaining ring 45 surrounding the upper part of the bearing ball above its axis, and secured to the adjacent part of the table by means of screws 46, as shown in Figs. 3, 9 and 10. By this means wax plates of considerable weight can be placed upon the table and adjusted with ease and facility thereon in a position to be engaged by the conveyer and propelled through the machine so as to expedite the wax removing and plate straightening operations.

In order to center the wax-coated plates on the table preparatory to moving the same forwardly to the wax removing and plate straightening devices, centering means are provided which preferably consist of two centering arms 47 which are arranged on opposite sides of the path of waxed plates and are pivoted at their rear ends by means of vertical screws or pins 48 to the upper side of the table at the rear end thereof while their front ends are yieldingly pressed inwardly so that the two centering arms converge forwardly and serve to engage opposite longitudinal edges of the waxed plates. The spring means which operate to yieldingly press these centering arms inwardly toward each other are combined with means which also limit the inward movement of these arms toward each other. The preferred form of this pressing and stopping means, as shown in the drawings, comprise two stop rods 49 each of which is connected at its inner end by a vertical pin 501 with the outer side of one of the centering arms while its outer end passes through a guide lug 50 on the adjacent part of the bed and an adjustable stop screw 51 arranged on the outer end of each stop rod 49 and adapted to engage with the outer side of the respective lug 50, and an expansion spring 52 surrounding the stop rod 49 and bearing at its outer end against the respective lug 50 while its inner end bears against a shoulder 53 on this stop rod, as best shown in Figs. 1 and 3.

Although various means may be employed for adjusting the table and the cover relatively to each other those shown in the drawings have been found satisfactory and as there

shown the same comprise a plurality of vertical adjusting screws 54 each of which is secured at its lower end by a screw joint in a lug 55 on the side portion of the table and is held 5 against turning therein by means of a clamping nut 56 while the upper end of each of these adjusting screws passes through a lug 57 on the adjacent side portion of the cover and is adjustably secured thereto by means of upper 10 and lower clamping screw nuts 58, 59 arranged on this screw and engaging with the upper and lower sides of the respective lug 57, as best shown in Figs. 1, 3 and 5. Upon loosening the lower adjusting screw nuts 59 and 15 tightening the upper screw nuts 58 the cover 24 is lowered relatively to the table, while upon loosening the upper screw nuts 58 and tightening the lower screw nuts 59 this cover will be raised relatively to the table, whereby 20 the passage way or gap between the table and cover may be regulated in the height as desired or required to suit any particular thickness of waxed plate which is being treated in the machine.

25 The bulk of the wax is removed from the plates as the same pass over the table and under the cover by applying heat to the waxed plates during this time. The preferred means for thus heating the waxed plates which are 30 shown in the drawings consist in providing the under side of the table with a heating chest, oven or jacket 60 and also providing the cover 24 on its upper side with a heating chest, oven or jacket 61, through which jackets 35 the heating medium of any suitable character may be passed so as to impart the required heating effect to the waxed coated plates which will operate to melt the wax on these plates and cause the same to run off from the 40 plates on to the table and thence flow over the edges of the table to suitable means which receive the same and collect the wax in a condition to be used over again. In the preferred construction of this machine the same is organized to utilize steam heat as the medium 45 for heating the ovens, chests or jackets of the table and cover. In order to cause this steam to operate most effectively on the table the interior of the heating chest 60 thereof is partitioned by a plurality of baffles 62 into a circuitous passage or conduit which extends 50 from one end of the lower heating chest 60 to the other and steam is admitted through an inlet 63 at one end of this chest, preferably the 55 rear end thereof and the water of condensation is discharged through an outlet 64 thereof.

The upper heating chest of the cover 24 is similarly provided on its interior with a 60 plurality of baffles 65 which forms a serpentine passage therein, the front end of which is provided with an inlet 66 for the live steam while the rear end thereof is provided with an outlet 67 for the escape of the water 65 of condensation. The steam which is sup-

plied from any suitable source is delivered by a pipe 68 into the inlet 63 of the lower steam chest 60 and after passing through the latter it passes out through the outlet 64 at the front end thereof and is then delivered 70 to the inlet 66 of the upper steam chest 61 and after passing through the latter it escapes through the outlet 67 thereof to a discharge pipe 69. In order to permit the upper steam chest 61 to be adjusted vertically together 75 with the cover 24 a flexible piping connection is provided between the lower and upper steam chests which preferably consist of a longitudinal vertically swinging intermediate pipe 70 connected by front and rear ball 80 joints 71, 72 with the outlet of the lower steam chest and the inlet of the upper steam chest, as shown in Figs. 1 and 3. To permit of raising and lowering the upper steam chest the discharge pipe 69 is made flexible. By 85 this means the two steam chests can be freely adjusted relatively to each other without distorting the connection of the heating pipes between the same.

Immediately in rear of the cover 24 and its heating chest a main or primary scraper 73 is provided which operates to scrape off either all or a part of the remnants of wax which may still adhere to the upper surface of the waxed plate as the same emerges from underneath the top steam chest 61. This main scraper is preferably constructed in the form of a blade which inclines vertically and has its lower scraping edge arranged rearwardly of its upper attached edge, as shown 95 in Fig. 2, so that the wax removed from the plate 26 is lifted thereby, and this plate also is arranged obliquely with reference to the forward movement of the plate, as shown in 100 Figs. 1 and 3, whereby the wax removed from the plate is gradually worked toward one side of the table in the manner of a plough and discharged over one of the longitudinal edges of the table. This main scraper 73 is secured at 105 its upper edge to a transverse bar 74 which is mounted at its opposite ends in blocks 75 which are seated in upwardly opening sockets 76, 77. These sockets may be supported in any suitable manner, for instance the socket 76 may be mounted on the front part 110 of the steam chest 61 and the socket 77 may be mounted on the adjacent part of the bed, as best shown in Figs. 1, 2 and 3.

As each plate 25 is discharged from the front end of the table 23 the same is subjected on its upper side to another scraping operation whereby any small remnants of wax which may be deposited thereon and removed therefrom are dropped in front of the table to be subsequently disposed of in the manner which will be described further on. For this purpose an auxiliary or secondary scraper 78 having preferably the form of an upright blade is arranged transversely above 125 the space immediately in advance of the front 130

end of the table and mounted at its upper end on a shaft 79 which is journaled at its opposite ends in bearings 80 on the main frame. In its normal upright position this secondary scraping blade bears with its rear side against a stop 81 formed in a standard constituting part of the main frame and this blade is yieldingly held in this position by means of a spring 82 bearing at one end 10 against the front side of the blade 78 while its opposite end bears against a screw 83 which is mounted on an adjacent bracket forming part of the main frame. As the wax-coated plate is moved forwardly by the 15 carrier against the auxiliary blade 78 the latter is deflected forwardly and caused to bear with its lower edge against the top of the plate 25 and thereby remove from this plate any remnants of wax which may still 20 be deposited thereon or adhere thereto. Any wax which is thus removed is discharged from the rear end of the plate into the space immediately in front of the table 23. The auxiliary scraper 78 upon clearing the rear 25 end of the plate is automatically returned by the springs 78 into its normal vertical position in which the same engages with the stop 81 preparatory to engaging with the upper side of the next plate.

30 Due to handling the plates 25 and also heating the same and subjecting the same to the scraping action for the purpose of removing the wax therefrom these plates are liable to become bent or warped to some extent. In 35 order, therefor, to restore these plates to a flat condition before they leave the machine and thus put the same in condition for re-use, pressing means are provided which operate upon the plates to flatten and straighten 40 them. The means for thus pressing the plates which are shown in the drawings comprise two large heavy pressing rollers 84, 85 which are arranged transversely and horizontally over the front part of the table 23 which projects beyond the front end of the cover 24 and 45 are adapted to project with their lower sides into the path of the part of the electrotype plates 25 so that the latter are subjected by these rollers to a downward pressure against the 50 table 23 while the plates are being moved forwardly by the conveyer thereby removing any wrinkles, waves, bends or other deformation from the plates before they leave the machine. Each of these pressing rollers is preferably 55 so mounted that the same is capable of yielding vertically and thereby adapt itself automatically to any slight variations which may exist in the thickness of the electrotype plates 25 which are being operated upon.

60 For this purpose each of the pressing rollers is provided on its opposite ends with trunnions 86 which are journaled in bearings 87 movable vertically in guideways 88 on the adjacent part of the main frame. These bearings 65 are yieldingly held in a depressed posi-

tion by means of springs 89 each of which engages with its lower end against the upper side of one of the bearings 87 while its upper end bears against the lower end of an adjusting screw 90 mounted on a cross bar 91 forming part of the main frame of the machine, as best shown in Fig. 12. By this means the resilience of the springs 89 together with the weight of the pressing rollers operate to furnish the requisite pressure which, when applied to the upper side of the electrotype plates 25 serves to flatten and straighten them during the last part of the movement of these plates over the table 23. By turning the screws 90 in one direction or the other the resilience of the springs 89 may be adjusted for adapting the pressure of the rollers to suit the requirements of the electrotype plates.

While the electrotype plates are thus subjected to pressure for flattening and straightening them they are also heated on the under side by the steam chest of the table 23 and on the upper side by circulating a heating medium through the pressing rollers, thereby facilitating the flattening and straightening 90 operation of these plates. In order to permit of thus circulating a heating medium through these rollers the same are made hollow, as shown in Figs. 2 and 6 and each of the trunnions 86 of these rollers is also made hollow 95 and steam or other heating medium is conducted into each of these rollers through the trunnion on one end thereof and the spent or partly spent heating medium is carried off from the respective roller through an outlet 100 in the opposite trunnion thereof. In Fig. 6 a typical form of a rotary pipe connection is shown for admitting the steam at one end of the roller and discharging the same from the opposite end thereof, which pipe connection as 105 there shown, comprises a nipple 92 extending axially through the respective hollow trunnion 86 and a stuffing box 93 which forms a leak-tight joint between this nipple and the trunnion of the roller. In the preferred construction one end of the front pressing roller 85 is connected with the corresponding trunnion 86 of the roller 84 by means of a transfer pipe 95. Of the trunnions at the opposite 110 corresponding ends of the rollers 84, 85, one 115 of them connects with the steam supply pipe 68 by a branch 94 and the other is connected by a branch discharge pipe 96 with the discharge pipe 69 of the upper steam chest.

By means of this construction steam or 120 other heating medium is conducted into the end of one of the pressing rollers and discharged from the opposite end thereof, then this heating medium is admitted into one end 125 of the other pressing roller and discharged from the opposite end thereof, in parallel with the course of the steam which is supplied to the upper and lower heating chests 60, 61 of the table and cover. The rotary connection between the heat conducting pipes 130

and the pressing rollers permits the latter to not only rotate freely a requisite extent but also enables these rollers to rise and fall as much as is required for which sufficient play is provided between the bearings 87 and the vertical guides in which the same slide.

The wax which is removed from the electrotype plates due to its melted condition flows from the top of the table 23 downwardly 10 along opposite longitudinal edges thereof into longitudinal curbs or channels 97 which are arranged on opposite longitudinal sides of the table 23. From the central parts of these curbs the melted wax is conducted downwardly and backwardly by means of spouts 98 to the under side of the lower steam chest 60 and into the central parts of an upwardly opening pan 99 which is arranged lengthwise on the under side of the steam chest 60 and 20 extends at its front and rear ends beyond the front and rear ends of the lower table 23 and provided at its front and rear ends with upwardly projecting transverse shields 100, 101 forming upright passages 102, 103 between 25 the corresponding front and rear ends of the table and the pan 99. The latter, therefore, catches any wax which may flow either off from the longitudinal edges of the table or from the front and rear edges thereof or 30 which may be removed by either of the scrapers 73 and 78 from the electrotype plates. The passages 102 and 103 also form spaces in the bed of the machine which receive the delivery 35 sprocket wheels 30 and the receiving sprocket wheels 29 respectively and those parts of the carrier chains passing around the same. The bottom of the pan 99 slopes to the center thereof at which last mentioned point the same is provided with an outlet 104 which 40 communicates with a spout 105 extending downwardly and laterally to a kettle 106 into which the wax is delivered by the spout 105 from the pan 99 preparatory to again using the wax for cutting electrotyping plates.

In order to remove any solid particles from the wax before it reaches the kettle 106 a screen 107 is arranged in the pan 99 over the outlet 104 thereof, thereby retaining any refuse which may be present in the wax such 50 as small particles of metal which may have been scraped from the electrotype plates and ensuring the delivery of only clear wax to the wax kettle 106 for subsequent use.

It has been found in practice that the wax 55 will cool and cease to flow over the bottom of the pan 99 and through the spout 105 unless the same is maintained in a heated condition sufficient to keep the wax melted. In order to accomplish this a heating pipe 108 is arranged along the bottom of the pan 99 and connected at its inlet end by means of a branch pipe 109 with the outlet pipes 69, 96 of the upper steam chest and the rear pressing roller 86, and a similar pipe 110 is arranged lengthwise 60 within the spout 105 and connected at

its upper inlet end with the outlet of the pipe 108 while its lower discharge end is connected by means of a pipe 111 with the return side of the boiler or other source from which the steam is supplied. By this means the heating 70 medium in the case of steam is constantly in circulation both through the steam chests, the pressing rollers, the catch pan or basin 99 and the delivery spout 105 so that the table and cover are properly heated to cause the 75 wax to be removed from the plates, the pressing rollers to be heated so as to facilitate flattening or straightening of the electrotype plates and the catch pan 99 and associated parts to be sufficiently heated to ensure 80 a free flow of the wax from the machine to the place of deposit which has been provided for the same.

Means are provided for automatically ejecting the electrotype plates from the machine after the wax has been removed therefrom and also stacking the same in a pile so that they are conveniently available and ready for subsequent re-use, these means being constructed as follows:—

The numeral 112 represents a vertically movable receiving or stacking table which is arranged in front of the table 23 and the pan 99 and upon which the electrotype plates 25 are adapted to be stacked one upon another 95 to form a vertical pile. This stacking table when empty is arranged flush or substantially so with the upper side of the table 23 so that the electrotype plate 25 may be pushed directly from the table 23 on to this stacking table, 100 as shown in Fig. 2. The stacking table 112 is yieldingly held in its elevated position but is lowered automatically a distance equal to the thickness of an electrotype plate whenever such a plate is moved forwardly by the 105 propeller or conveyer over the heating table 23 and under the pressing rollers 84, 85, thereby causing the electrotype plates to be stacked or piled successively one upon the other in the same measure in which the cleaning of 110 the plates progresses. For this purpose the table 112 is guided in its vertical movement by means of guide lugs 113 on opposite longitudinal sides of the table and sliding in vertical ways 114 formed on the inner sides 115 of the front parts of the standards 21. This table is yieldingly held in its elevated position by means of weights 115 arranged adjacent to the outer sides of the lower parts of the standards 21, guide pulleys 116 arranged 120 above the standards 21 and lifting lines or cords 117 each passing with its upper turn around one of the pulleys 116 and connected at one end with the stacking table at one side thereof while the opposite end of this line is connected with one of the weights 115, as shown in Figs. 1, 2, 3, 4 and 12. The two guide rollers 116 are secured to opposite ends 125 of a transverse shaft 118 which is journaled in bearings 119 at the upper end of the stand-

130

ards 21. The weights 115 are sufficiently heavy so that they will counterbalance the stacking table 112 and any electrotype plates which may be resting thereon and tend constantly to hold this table and the plates thereon in an elevated position so that force is required to depress the same. This force is supplied by the movement of the electrotype plates forwardly over the table 23 under the action of the horizontal plate conveyer and in its preferred form the means whereby this movement is transmitted from the horizontally movable electrotype plates to the stacking table 112 for depressing the latter is constructed as follows:—

The numeral 120 represents two ratchet wheels secured to opposite ends of the shafts 118 and 121, two detent pawls pivoted on the upper ends of the standards 21 and each adapted to engage the teeth of one of the ratchet wheels 120 for the purpose of preventing backward rotation of the shaft 118 or in a direction which would permit the stacking table 112 to rise. The numeral 122 represents two feed pawls each of which engages one of the ratchet wheels 120 and is pivoted at its rear end on the lower end of a rock arm 123. The rock arms 123 of both feed pawls 122 are arranged vertically on opposite sides of the bed or frame of the machine and are secured at their upper ends to a rock shaft 124 which is journaled in bearings 125 arranged between the guideways 88 on the main frame for the bearings of the pressing rollers. Projecting downwardly from the rock shaft 124 is a tappet 126 having preferably the form of a plate which is adapted to have its lower end arranged in the path of the electrotype plates 23 so that the latter during its forward movement deflects this tappet forwardly and causes the shaft 124 to be rocked in the direction for causing the feed pawls 122 to turn the ratchet wheels 120 one space or to a sufficient extent to lower the stacking table 112 a distance equal to the thickness of one of the electrotype plates, thereby lowering the table and the plates resting thereon a sufficient distance to provide clearance at the top of the stack for the electrotype plate which is about to leave the table 23 and to be deposited on the stacking table. When the tappet 126 clears the rear end of the electrotype plate with which it has been engaged this tappet again drops into its normal pendant position into the path of the next following electrotype plate, as shown in Fig. 2, ready for producing the next depressing operation upon the table under the action of an electrotype plate which passes through the machine. This return of the tappet 126 to its normal pendant position and also the backward motion of the two feed pawls 122 is effected by gravity due to the weight of these parts being sufficient for this purpose but obviously spring means may be employed

in place of gravity or in addition thereto in an obvious and well known manner.

The means whereby the electrotype plates are successively transferred from the front end of the heating table 23 to the stacking table 112 or the plates resting thereon are constructed as follows:—

The numeral 127 represents a shifting bar or rod arranged horizontally and transversely over the path of the electrotype plates between the front end of the heating table and the rear edge of the stacking table 112 and having a forward and backward reciprocating movement relatively thereto. This motion may be imparted to this shifting bar in any suitable manner but preferably by means which comprise two upright shifting bars 128 arranged in an upright position adjacent to the outer side of the bed or frame of the machine and each having its lower end connected with the main frame by means of a guide link 129 while its upper part is provided with a guide pin 130 moving in a guide slot or way 131 on the adjacent upper part of the main frame, while the intermediate part of this shifting bar is provided with an upright slot 132 which receives a crank pin 133 which rotates with the adjacent part of the shaft 32. On one side of the machine this crank pin is mounted on the outer side of the sprocket wheel 41 which is available for this purpose and on the other side of the machine a crank disk 134 is provided which forms the same function as the sprocket wheel 41 so far as supporting the crank pin 133 on the shaft 32 is concerned. On its under side the supporting or shifting bar 127 is provided with a plurality of feeding dogs 135 which are yieldingly mounted on the bar 127 so that during the backward motion of this bar these dogs will yield and trip or slide idly backwardly over the top of the respective electrotype plate which is being fed forwardly by the longitudinal conveyer, but during the last part of the backward stroke of this bar said dogs will be projected into their lowermost or operative condition in rear of the rear edge of the electrotype plate so that during the subsequent forward motion of the shifting bar 127 these dogs will engage the rear edge of the electrotype plate and move the same forwardly from the position where they were left by the wings of the longitudinal conveyer to a position in which this plate will be arranged in its foremost position and in alignment with the pile of plates on the stacking table. For this purpose each of the dogs is provided with an abrupt front side 136 and an inclined rear side 137 and its upper part is guided in a screw plug 138 which is secured in the lower end of a socket 139 formed in a bracket 140 which is secured with its upper part to the supporting or shifting rod 127. Downward motion of the

dog 135 is limited by engagement of a collar or shoulder 141 on the upper end of this dog with the upper end of the screw plug 138, and this dog is yieldingly held in its lowermost or depressed position by means of a spring 142 arranged in a socket 133 and bearing at one end against the top of this socket while its lower end bears against the upper end of the dog 135, as best shown in Fig. 8. As 10 the shifting bar 127 moves backwardly each of the dogs 135 by engaging its inclined rear side 137 with the electrotype plate which has previously been deposited on the front end of the table 23 by a longitudinal conveyer, 15 will clear this plate. At the end of the rearward motion of the shifting bar 127 each dog 135 will be projected downwardly by its spring 142 so that during the subsequent forward movement of this bar the abrupt front side 136 of each dog will engage the 20 rear edge of the electrotype plate and move the same forwardly until the rear edge of this plate is clear of the bed of the machine and wholly on top of the stacking table, as 25 shown in Fig. 2.

Whenever the operator removes some or all of the wax stripped plates from the stacking table 112 the latter is disconnected from its depressing mechanism and permitted to 30 rise as far as necessary by disengaging both the feed pawls and the detent pawls from the ratchet wheels 120 whereby the weights 115 are permitted to elevate the stacking table 112. Such disengagement of the detent pawls 35 and feed pawls is preferably effected by providing each of the detent pawls with a handle 143 which may be grasped by the operator for disengaging this pawl from the ratchet wheel 120 and also providing each of these de- 40 tent pawls with a rearwardly, projecting lifting arm 144 which engages underneath a lifting pin 145 on the companion feed pawl 122, so that when each detent pawl is moved upwardly and forwardly out of engagement 45 from the respective ratchet wheel, the companion feed pawl 122 will be simultaneously moved upwardly and rearwardly out of engagement from the ratchet wheel, thereby facilitating the release of the stacking table 50 from its depressing mechanism and the restoration of the same to its more or less elevated position.

As a whole this machine is comparatively simple considering the various functions 55 which it performs, the same permits of expeditiously and efficiently removing the wax from electrotype plates so that the same can be kept in service more continuously and thus permit of reducing the number of plates required for this purpose, it also automatically performs the operation of straightening or flattening the plates if the same at any time become bent or misshapen, and the same is also very compact in construction and 60 capable of being installed where only a lim- 65

ited amount of space is available for such a machine.

I claim as my invention:

1. A machine for removing wax from plates, comprising a table adapted to be heated, and a conveyor for propelling said plates over said table including an endless belt having an upper stretch movable over said table, a lower stretch movable under said table, wings arranged on said belt and adapted to engage the rear end of said plates, and wheels which are arranged at opposite ends of said table and around which said belt passes, said table being provided on its upper side with a longitudinal groove which receives the upper stretch of said belt. 70

2. A machine for removing wax from plates, comprising a lower table, an upper cover arranged above the table and forming a passage there between, means for heating the table and cover and a conveyor for moving said plates through said passage. 85

3. A machine for removing wax from plates, comprising a comparatively long table, means for heating the table, a comparatively short cover which is arranged over the table and terminates at its front and rear ends short of the corresponding ends of the table, means for heating the cover, and means for moving said plates between said table and cover from 90 one end to the other thereof. 95

4. A machine for removing wax from plates, comprising a lower table, an upper cover arranged above the table, means for heating said table and cover, means for moving said plates between said table and cover, and means for adjusting said cover relatively 100 to said table.

5. A machine for removing wax from plates, comprising a lower table, an upper cover arranged above the table, means for heating said table and cover, means for moving said plates between said table and cover, and means for adjusting said cover relatively 105 to said table comprising lugs arranged on the corresponding parts of said table and cover, screws passing through corresponding lugs, and screw nuts arranged on said screws and engaging with said lugs. 110

6. A machine for removing wax from plates, comprising a table, means for heating the table, means for moving said plates over said table, and means for scraping the wax from said plates while the same are heated comprising an inclined blade the lower edge 115 of which is adapted to engage the plates and points toward the approaching plates. 120

7. A machine for removing wax from plates, comprising a table, means for heating the table, means for moving the plates over said table, and means for scraping the wax from said plates consisting of a blade which is adapted to engage its lower edge with the upper side of said plate and which is inclined 125 rearwardly from its upper front edge to its 130

lower rear edge so that its lower edge points toward the approaching plates and which is arranged so that one end of the blade is in advance of the other to the line of movement of the plates, and supports for said blade at opposite ends thereof.

8. A machine for removing wax from plates, comprising a table, means for heating the table, means for moving the plates over said table, and means for scraping the wax from said plates consisting of a blade which is adapted to engage its lower edge with the upper side of said plate and which is inclined rearwardly from its upper front edge to its lower rear edge so that its lower edge points toward the approaching plates and which is arranged so that one end of the blade is in advance of the other to the line of movement of the plates, a cover arranged over said table and in rear of said blade, means for heating the cover, and supports for opposite ends of said blade and said table and cover.

9. A machine for removing wax from plates, comprising a table, means for heating said table, means for moving said plates over said table, and means for scraping said plates consisting of a blade adapted to engage its lower edge with said plates, means for pivotally supporting said blade at its upper end, a stop for limiting the rearward movement of said blade, and a spring which holds said blade against said stop.

10. In a machine for removing wax from plates, a table, means for heating said table, means for moving the plates over said table, and means for pressing said plates against said table and flattening and straightening the same.

40 11. In a machine for removing wax from plates, a table, means for heating the table, means for moving the plates over said table, and means for pressing said plates against said table and flattening and straightening the same comprising a roller adapted to engage the upper side of said plates.

12. In a machine for removing wax from plates, a table, means for heating the table, means for moving the plates over said table, means for pressing said plates against said table and flattening and straightening the same comprising a roller adapted to engage

the upper side of said plates and means for heating said roller.

13. In a machine for removing wax from plates, a table, means for moving the plates over said table, means for heating said plates while on said table and melting the wax thereon and means for catching the melted wax flowing from said table.

14. In a machine for removing wax from plates, a table, means for moving the plates over said table, means for heating said plates while on said table and melting the wax thereon and means for catching the melted wax flowing from said table comprising curbs arranged along the edges of said table and provided with spouts, a pan arranged below the table and receiving the wax from said spout, and a kettle which receives the wax from said pan.

15. In a machine for removing wax from plates, a table, means for moving the plates over said table, means for heating the plates while on the table and melting the wax thereon, conduits for carrying away the melted wax from said table, and means for heating said conduits and maintaining the wax therein in a flowing condition.

16. In a machine for removing wax from plates, a table, means for moving the plates over the table, means for heating the plates, and rolling bearings which support the plates deposited on said table.

17. In a machine for removing wax from plates, a table, means for moving the plates over the table, means for heating the plates, and rolling bearings which support the plates deposited on said table consisting of bearing balls mounted on the undersides in said table, and retaining rings surrounding the upper parts of said balls and secured to said table.

18. In a machine for removing wax from plates, a table, means for moving the plates over the table, means for heating the plates and means for centering said plates on said table comprising forwardly converging guide arms pivoted at their rear ends on the table, springs for pressing the front ends of said arms inwardly, and means for limiting the inward movement of said arms.

ANDREW R. KOEHLER.
